UNITED STATES PATENT OFFICE.

ECKLEY B. COXE, OF DRIFTON, PENNSYLVANIA.

TRAVELING-FLOOR FURNACE.

SPECIFICATION forming part of Letters Patent No. 536,372, dated March 26, 1895.

Application filed July 30, 1894. Serial No. 518,918. (No model.)

To all whom it may concern:

Be it known that I, ECKLEY B. COXE, a citizen of the United States, residing at Drifton, in the county of Luzerne and State of Pennsylvania, have invented certain new and useful Improvements in Traveling-Floor Furnaces, of which the following is a specification.

This invention relates to that class of furnaces having means for imparting a traveling movement to the fuel within the furnace-chamber; and the invention is more particularly intended as an improvement upon furnaces of this class employing reciprocatory furnace-floors for imparting a traveling movement to the fuel.

It is the object of my present invention to provide, in connection with a furnace of this class, a fuel-traveling furnace-floor comprising a plurality of floor-sections adapted to have an oscillatory movement, and to provide mechanism in connection with, and adapted for imparting slightly oscillatory but parallel movements to, said floor-sections, and in such manner that they will have a relatively slow forward movement and a relatively rapid backward movement either separately or successively, and will upon the inauguration of or during this movement subject the fuel to a slight agitation or vertical movement sufficient to loosen the mass, break the continuity thereof, and in a great measure prevent adhesion of cinders or burning fuel to the furnace-floor, thereby securing the best practical results with regard to uniformity in the traveling movement of the fuel, at the minimum expense of power.

Another object of the invention is to secure simplicity, durability and efficiency in the furnace-floor-supporting and actuating mechanism.

In the drawings accompanying and forming part of this specification, Figure 1 is a sectional plan view of a furnace of the class specified embodying my present invention. Fig. 2 is a vertical longitudinal section of the same, taken in line $a-a$, Fig. 1. Fig. 3 is a vertical cross-section of the furnace, on an enlarged scale, taken in line $a-a$, Fig. 2, looking toward the right-hand in said figure. Figs. 4, 5 and 6 are side views of the swinging frames which support, and permit the os-

cillating movement of, the successive floor-sections which comprise the furnace-floor. Figs. 7, 8, 9, 10 and 11 are sectional views of 55 a floor-section, one of its supporting frames, and the operating mechanism therefor, said figures showing the operation of the actuating mechanism for the furnace-floor, and illustrating five successive positions assumed by 60 the floor-section in its forward and backward movements. Fig. 12 is a sectional side elevation of one member of one of the floor-sections actuating cams, on an enlarged scale, said figure also being in the nature of a diagram 65 illustrating the comparative equations of velocity of the advancing and retracting cam-faces thereof. Fig. 13 is a cross-section of said cam-member, taken in dotted line $x-x$, Fig. 12, looking downward in said figure. 70 Fig. 14 is a similar cross-section, taken in line $x-x$, Fig. 12, looking upward in said figure. Fig. 15 is a profile or diagram showing the graphic equation of the grate-section velocity.

For the purpose of illustrating the application and utility of my present invention, I have shown my improvements applied to a furnace similar to the one described in Letters Patent of the United States No. 499,716, granted to me June 20, 1893, to which reference may be had. In the present instance, however, the furnace-chamber designated by C is shown covered for a considerable portion of its length by a reverberatory roof, A; and a boiler, B, (a portion only of which is shown,) 80 is supported over the rearward portion of said furnace-chamber. It will be understood, however, that my improvements are applicable to any form of furnace having a furnace-chamber capable of receiving a traveling furnace-floor.

In the furnace partially shown in the drawings, the furnace-chamber C is inclosed by the usual side-walls, 2 and 4, is covered by a roof, A, which in practice will be made of fire-brick or other like material, and the front and rear end-walls, 3 and 5, respectively, and also has the usual bridge-wall, 7, at the rear end of said furnace-chamber. In the front end-wall 3 is a passage-way, 5', through which fuel is supplied to the furnace-floor. At the forward end of the furnace, this is shown supplied with the usual fuel-supply hopper, H, from which fuel is supplied to the furnace-

floor through the inclined chute or opening 5', in a well-known manner.

The furnace is shown provided with a fuel-traveling furnace-floor or grate, designated 5 in a general way by K, and which in accordance with my present invention consists of a plurality of alternate series of independent floor-sections or grate-sections, which sections comprise a plurality of grate bar-supporting 10 beams and a series of grate-bars carried by said beams. The beams of these successive series of grate-sections are designated by E, F, and G, respectively, the aggregate number of grate-beams in the entire series being 15 herein shown as thirteen, and the grate-bars carried by said beams are designated by M. It will be understood, however, that the number of grate-sections employed will, in practice, depend upon the width of the furnace- 20 chamber and the size of the grate-sections it is desired to use.

As a means for supporting the beams E, F and G of the three successive series of grate-sections and providing for a slight oscillatory 25 as well as a parallel movement thereof, each series of grate-beams is shown independently supported at the upper ends of a set of oscillatory carriers or swinging frames, E', E², F', F²; and G', G², respectively, which frames are 30 shown pivotally supported at their lower side-edges, preferably by trunnions, 10, in sockets or bearings 10' preferably secured to the inner faces of the side-walls 2 and 4 of the furnace, as most clearly shown in Figs. 2 and 3 35 of the drawings, the oscillating carriers or swinging frames E', F' and G' being preferably located adjacent to the forward end of the grate-beams, and the ones E², F² and G² being located near the rearward end of the 40 grate-beams, as shown in said Fig. 2.

The successive sets of swinging carrier-frames E', E²; F', F²; and G', G², which are 45 preferably of angular truss-like construction, are provided at their upper ends with a series 50 of equi-distantly disposed grate-section supporting arms, e³, f³ and g³, the supporting arms of the three sets of carrier-frames being so disposed relatively to each other and with relation to the length of said frames, or the 55 width of the furnace-chamber, as to alternate one with the other, each set of swinging frames supporting a series of grate-sections and each being capable of movement independent of the succeeding set. These floor- 60 section-carrying frames, as before stated, are provided at their lower ends at opposite edges thereof with trunnions, 10, which are removably-supported in sockets, 10', secured preferably to the side-walls of the furnace-chamber, as clearly shown in Figs. 2 and 3 of the 65 drawings. The swinging frames of each set of frames are in parallel disposition with relation to each other and extend below the grate-sections transversely at right angles to the length thereof, as will be understood by reference to said Figs. 2 and 3. The upper end of the carrying arms e³, f³ and g³ will

preferably be rounded slightly, to reduce friction.

In connection with the several series of 70 grate-sections, I have shown provided actuating-mechanism adapted for imparting a relatively slow advancing movement and a relatively rapid retractive movement to the successive series of grate-sections, the construction and operation of which will be hereinafter described.

Underneath the furnace-floor or grate-sections is placed an air-blast apparatus, which, in the preferred form thereof herein shown, 80 comprises the successive air-blast chambers a, b, c and d, which may be of the same general construction and arrangement as the air-blast chambers described in the Patent No. 499,716 hereinbefore referred to. In this instance, however, the dividing-walls a', b' and c' are each shown having openings, 8, therethrough communicating with the next adjacent chamber, and slide-valves, or gates, 8', are provided adjacent to said communicating 90 openings for regulating the areas of said openings, which valves may be similar in construction and operation to those described in Letters Patent of the United States No. 510,574, granted to me December 12, 1893. 95 Preferably, air is supplied from a supply-pipe, P, which is supplied from any suitable air-supply, first to the air-chamber b, it passing thence into the air-chambers a and c at opposite sides of the chamber b, and thence from chamber c into chamber d, as will be readily understood by reference to Fig. 2 of the drawings. The chamber d at the rear end of the furnace-chamber C not only constitutes an air-chamber for supplying air to 105 the fuel, but also constitutes an inclosing chamber for the grate-section carriers or frames E², F² and G², and the chamber a at the forward end of the furnace likewise constitutes an inclosing chamber for the grate-section carriers or frames E', F' and G', and the grate-section-actuating mechanism, as will also be seen by reference to Fig. 2 of the 110 drawings.

In the form thereof herein shown, the grate-beams are normally supported in parallelism side by side and are longitudinally-disposed with relation to the furnace-chamber C, and each grate-beam is in the nature of a channel-rail having a pocket or socket, 9, at the 115 underside and at each end thereof, to receive the actuating or supporting arms, 11, of the swinging carrier-frames; and each beam will preferably have a series of remotely-disposed dovetailed transverse flanges 12 at the upper 120 faces thereof, adapted for receiving, each, one or more grate-bars or floor-plates, M, which 125 grate-bars or floor-plates may be substantially the same as the grate-bars or floor-plates described in United States Patent No. 515,656, 130 granted to me February 27, 1894; which grate-bars are provided at their under sides with depending lips, 13 and 13', and are held in place upon the grate-beam by the interlock-

ing engagement of said lips with the side-edges of the transverse flanges 12 upon the grate-beam, said grate-bars being each provided with laterally-projecting lugs, 13", at 5 one side-edge thereof, which bear against the face of the next adjacent grate-bar, leaving a space between said bars for the passage of air from the air-chambers to the fuel supported upon said grate-bars.

10 The several series of grate-beams E, F and G, respectively, and their grate-bars M, comprising the grate-sections, are adapted to have, all together, or the major portion of them, a relatively slow forward movement, and to have 15 successively a relatively quick return or backward movement. Said successive series of grate-sections, or the major portion of them, are simultaneously advanced toward the left-hand in Figs. 1 and 2 by means of suitable 20 actuating-devices, as will be hereinafter fully described, and during said advancing movement the remaining series will be retracted to their original positions. In other words, a quick-return movement is imparted to one 25 or more of said series of grate-sections while the remaining series are completing their advancing movement, or moving in opposition to the direction of the return movement of said first-mentioned series.

30 As shown most clearly in Fig. 3 of the drawings, the beams E, F and G, comprising with their grate-bars the successive series of grate-sections, are so disposed that the beams E of one series will be adjacent to or lie between 35 the beams F and G of the other series. The beams F will lie between the beams E and G, and the beams G will lie between the beams E and F; so that the beams of one series will alternate with the beams of the other series.

40 By this construction and organization, the layer of fuel, designated by L, resting upon the grate-sections is carried uninterruptedly forward toward the rear end of the furnace with a uniform movement coinciding with the 45 forward movement of the majority of said sections, thus securing practically the same results as are obtained in a furnace employing an endless traveling grate such, for instance, as is shown in the Patent No. 499,716 herein- 50 before referred to.

During the quick-return movement of a portion of the grate-sections while the majority of the grate-sections have a movement in the opposite direction, the fuel, resting in a 55 mass upon the entire series of grate-sections, has a greater resistance upon the several adjacent forwardly-moving grate-sections than it has adhesion upon the fewer backwardly-moving grate-sections. Therefore the layer 60 or mass of fuel remains unbroken and comparatively unaffected by the retractive movement of the relatively few grate-sections.

The actuating-mechanism for imparting a relatively slow advancing movement and a 65 quick-return, or a relatively-rapid retractive, movement to the alternating series of grate-sections, will preferably be in the nature of

cam-and-lever mechanism, which in the preferred form thereof herein shown consists of a series of double cams or sets of cams, designated by m, n and o, respectively, there being one set or one double cam for each series of grate-sections, which cams are carried by a transverse shaft, 15, journaled in bearings, 16 and 17, upon the side-walls of the furnace-chamber C, preferably contiguous to the air-chamber a. These cams m, n and o are operatively connected with the swinging carrier-frames E', F' and G' which support the forward ends of the series of grate-sections 80 E, F and G, respectively, by means of connecting-links, m', n' and o', which are pivotally-secured at one end to the said swinging carrier-frames and carry friction-rollers at their opposite ends which engage the working faces of the cams, as will be hereinafter more fully described.

As a means for rotating the cam-shaft 15, said cam-shaft will be provided at one end with a worm-wheel, represented by the dotted circle 40 in Fig. 2, which worm-wheel meshes with a worm, 41, carried by the driving-shaft, 42, which is supported in bearings, 43 and 43', upon the side-wall of the furnace-chamber, and is provided with a pulley, 44, 95 by means of which said shaft is rotated from any suitable source of power.

As a means for balancing and for practically obviating lateral stress upon the carrier-frame-actuating links m', n' and o' by their actuating-cams, these cams are each in the nature of a double cam, each cam comprising two duplicate members coincidentally disposed with sufficient space between them to permit the entrance and movement between 100 them of the end of a carrier-frame-actuating link, which link carries at this end, at opposite sides thereof, friction-rollers, 18, which bear on the working-faces of the two members which comprise the actuating-cam. Each 105 member of the actuating-cam comprises the main body-portion, 20, peripherally spiraled at 21 to form the eccentric cam-face for imparting the relatively slow advancing movement to the grate-section, and having a quick-drop or 110 let-off portion, 22, and the circumferentially-grooved extension 23 contiguous to said let-off portion, which groove, designated by 24, 115 forms the retracting cam-face, 25, for imparting the quick-return movement to the grate-section, as most clearly shown in Fig. 12 of the drawings, which figure shows the eccentricity of the spiral cam-face 21 and the degree of inclination of the retracting cam-face relatively thereto. In practice, the two members 120 of the actuating-cam will be joined together by a hub, 26, preferably formed integral therewith, which hub forms a stable bearing through which the cam-shaft is extended. These cams will be so disposed with relation 125 to each other upon the cam-shaft and will be so timed in their movements as to impart the requisite movements, serially, to the grate-sections.

The grate-section-actuating levers will preferably be slotted at their ends adjacent to the cams, and are carried by swinging links, 27, which are pivotally connected thereto at 5 one end and are pivotally connected at their upper ends to brackets, 28, secured to the upper wall of the air-chamber *a*, as clearly shown in Fig. 2 of the drawings, which construction and arrangement permits an oscillatory reciprocation of the grate-sections and secures a stability conducive to effective operation and durability of working parts.

In operation, assuming the rollers 18 of an actuating-lever to be in the position illustrated by the dotted circle 18 in Fig. 12 of the drawings, or in the position shown in full lines in Fig. 11, a rotation of the cam in the direction of the arrow will, owing to the eccentricity of the cam-face 21, bring the successive points designated by the dotted lines, *q*, *r*, *s* and *t*, successively, contiguous to said roller, moving the same outward together with the actuating-link, the carrier-frame connected therewith, and the grate-sections carried by said carrier-frame, from the position shown in Fig. 11, which is the extreme retractive position, to the position shown in Fig. 7, which is approximately the extreme forward position thereof, after which a continued rotation will bring successive portions thereof between the lines *t*, *u*, *v* and *w*, contiguous to the roller, retracting with a relatively quick movement the grate-section from the position shown in Fig. 7 successively to the positions illustrated in Figs. 8, 9, 10 and 11; which will be fully understood by reference to Figs. 7 to 12, inclusive, of the drawings. The velocity of the return movement as compared with the velocity of the advancing movement of said 40 mechanism, will be clearly apparent by an examination of Fig. 12 aforesaid.

It will be seen that while the grate sections have a reciprocatory movement in parallel lines, they also have a slight oscillatory movement, which, in practice, although hardly perceptible, will be sufficient, owing to the alternate movements of the several grate-sections, to break the continuity of the supported mass of fuel, and still with not sufficient abruptness to injuriously agitate said fuel.

Having thus described my invention, I claim—

1. In a furnace, the combination with the furnace-chamber, of a furnace-floor supported within said chamber and comprising alternating series of longitudinally-disposed grate-sections adapted for supporting a bed of fuel, a series of pairs of oscillatory frames disposed transversely of the furnace-chamber and in position and adapted for supporting and longitudinally oscillating said grate-sections, a series of arms fixedly secured to each frame of each pair and similarly disposed relatively to the arms of the other frame of its pair and alternately disposed relatively to the series of arms of the other pairs of said frames and in position and adapted for actuating one series of arms of the other pairs of said frames and in position and adapted for actuating one series

of grate-sections whereby said grate-sections are supported in alternating disposition relatively to the grate-sections of the other series, 70 and means in connection with and adapted for oscillating said frames with a relatively-slow forward movement and a relatively-rapid return movement and thereby carrying the fuel forward and vertically agitating the 75 same, substantially as described.

2. In a furnace, the combination with the furnace-chamber, of a furnace-floor supported within said furnace-chamber and comprising alternating series of longitudinally-disposed 80 grate-sections adapted for supporting a bed of fuel, a series of pairs of oscillatory frames disposed transversely of the furnace-chamber and in position and adapted for supporting and longitudinally oscillating said grate-sections, a series of arms fixedly secured to each frame of each pair and similarly disposed relatively to the arms of the other frame of its pair and alternately disposed relatively to the series of arms of the other pairs of said frames 85 and in position and adapted for actuating one series of grate-sections whereby said grate-sections are supported in alternating disposition relatively to the grate-sections of the other series, and a grate-section actuator in 90 connection with each pair of coacting frames and adapted to oscillate the same with a relatively-slow forward movement and a relatively-rapid return movement and thereby carry the fuel forward and vertically agitate 100 the same, substantially as described.

3. In a furnace, the combination with the furnace-chamber, of a furnace-floor supported within said furnace-chamber and comprising alternating series of fuel-supporting grate-sections disposed longitudinally of the furnace and adapted for movement in substantially the same horizontal plane, a series of pairs of oscillatory frames disposed transversely of the furnace-chamber and in position and adapted 110 for supporting and longitudinally oscillating said grate-sections, a series of arms fixedly secured to each frame of each pair and similarly disposed relatively to the arms of the other frame of its pair and alternately disposed 115 relatively to the series of arms of the other pairs of said frames and in position and adapted for actuating one series of grate-sections whereby said grate-sections are supported in alternating disposition relatively to the 120 grate-sections of the other series, and a grate-section actuator in connection with each pair of coacting frames and adapted to oscillate the same with a relatively-slow forward movement and a relatively-rapid return movement 125 and thereby carry forward the fuel supported on the grate-sections and vertically agitate the fuel, substantially as described.

4. In a furnace, the combination with the furnace-chamber, of a furnace-floor supported 130 within said furnace-chamber and comprising alternating series of longitudinally-disposed grate-sections adapted for supporting a bed of fuel, a series of pairs of oscillatory frames

- disposed transversely of the furnace-chamber and pivotally supported at their lower ends and in position and adapted for supporting and oscillating said grate-sections, a series of 5 arms fixedly secured to each frame of each pair and similarly disposed relatively to the arms of the other frame of its pair and alternately disposed relatively to the series of 10 arms of the other pairs of said frames and in position and adapted for actuating one series of grate-sections whereby said grate-sections are supported in alternating disposition relatively to the grate-sections of the other series, and a grate-section actuator in connection 15 with each pair of coating frames and adapted to oscillate the same with a relatively slow forward movement and a relatively-rapid return movement and thereby carry the fuel forward and vertically agitate the same, sub- 20 stantially as described.
5. In a furnace, the combination with the furnace-chamber, of a pair of oscillatory frames disposed transversely of the furnace-chamber and adjacent to opposite ends of the 25 grate-sections and having a series of remotely- and similarly-disposed arms fixedly secured to their upper sides and adapted for supporting and longitudinally oscillating the grate-sections, a series of grate-sections supported 30 at their opposite ends upon the arms of said oscillatory frames and adapted for supporting a bed of fuel, and means in connection with and adapted for oscillating said frames
- with a relatively-slow forward movement and a relatively-rapid return movement and thereby carrying forward the fuel and vertically agitating the same, substantially as described. 35
6. In a furnace, the combination with the furnace-chamber, of a furnace-floor supported within said furnace-chamber and comprising 40 alternating series of longitudinally-disposed grate-sections, a series of pairs of oscillatory frames disposed transversely of the furnace-chamber and in position and adapted for supporting and oscillating said grate-sections, a 45 series of arms fixedly secured to each frame of each pair and similarly disposed relatively to the arms of the other frame of its pair and alternately disposed relatively to the series of arms of the other pairs of said frames, and in 50 position and adapted for actuating one series of grate-sections whereby said grate-sections are supported in alternating disposition relatively to the grate-sections of the other series, and a cam-and-link actuator in connection 55 with and adapted for actuating each pair of oscillatory frames and thereby oscillating each of the grate-sections with a relatively- slow forward movement and a relatively-rapid return movement whereby the fuel is carried 60 forward and is vertically agitated, substantially as described.
